(57) **CLAIM**

The ornamental design for an endoscope, as shown and described.

DESCRIPTION

FIG. 1 is a perspective view of an endoscope showing our new design;

FIG. 2 is a top plan view thereof; with the shaft portion shown broken in the middle to represent indefinite length with an enlarged view of the tip portion shown enlarged for ease of illustration.

FIG. 3 is a front elevational view thereof; with the tip portion shown enlarged for ease of illustration.

FIG. 4 is a bottom plan view thereof; with the tip portion shown enlarged for ease of illustration.

FIG. 5 is a rear elevational view thereof; with the tip portion shown enlarged for ease of illustration.

FIG. 6 is a right side elevational view thereof; with the tip portion shown enlarged for ease of illustration.

FIG. 7 is a perspective view a second embodiment;

FIG. 8 is a top plan view thereof; with the shaft portion shown broken in the middle to represent indefinite length with an enlarged view of the tip portion shown enlarged for ease of illustration.

FIG. 9 is a front elevational view thereof; with the tip portion shown enlarged for ease of illustration.

FIG. 10 is a bottom plan view thereof; with the tip portion shown enlarged for ease of illustration.

FIG. 11 is a rear elevational view thereof; with the tip portion shown enlarged for ease of illustration; and,

FIG. 12 is a right side elevational view thereof; with the tip portion shown enlarged for ease of illustration.

The broken line showing is for illustrative purpose only and forms no part of the claimed design.
